SPECTACLE CASE

Raymond F. E. Stegeman, Greece, N. Y., assignor to Bausch & Lomb Optical Company, Rochester, N. Y., a corporation of New York

Application April 19, 1954, Serial No. 423,955

5 Claims. (Cl. 206—5)

This invention relates to spectacle cases and more particularly it has reference to a spectacle case of the type having an open end for the insertion of a spectacle.

One of the objects of this invention is to provide an improved spectacle case of the type described having means for retaining the spectacle in the case without the use of flaps or closure devices.

Other objects of this invention are to provide an improved spectacle case of the type described which will be relatively simple in structure, efficient in operation, and capable of being manufactured at a relatively low cost.

These and other objects and advantages reside in certain novel features of construction, arrangement, and combination of parts as will hereinafter be more fully described and pointed out in the appended claims.

Referring to the drawing:

Fig. 1 is a side elevational view of a spectacle case embodying my invention, with parts shown broken away.

Fig. 2 is an elevational view of the open end of the case.

Fig. 3 is a side view of a modified form of case embodying my invention, with parts shown broken away.

Fig. 4 is an elevational view of an end thereof.

A preferred embodiment of my invention is disclosed in the drawings wherein 10 indicates a spectacle case having a substantially flat, tubular body portion which may be formed by reversely folding a piece of flexible sheet material such as leather, plastic or the like. The overlapping portions of the sheet material are secured together along their end and bottom edges by any suitable means such as stitching 11. This provides a substantially flat, tubular body member having front and rear walls 12 and 13, respectively, with one end closed and the other end open as at 16.

The upper portions of the walls 12 and 13, adjacent the open end 16 of the body, are partially cut away as shown at 14. The cut away portion of the walls 12 and 13 is partially filled in by a piece of elastic sheet material 15 which is reversely folded on itself and has its longitudinal and inner end edges secured to the adjacent portions of the walls 12 and 13 in any suitable manner such as stitching 17. The elastic sheet material 15 may, for example, be made of woven fabric with rubber threads combined.

The bottom longitudinal edges of the walls 12 and 13 are secured together along their adjacent edges so that the walls 12 and 13 extend upwardly in diverging relation, thereby making the bottom edge portion of the body member substantially V-shaped in vertical section. This V-shaped longitudinally extending bottom edge portion provides a track on which the bottom part of a spectacle will slide when it is inserted in the case.

From the foregoing, it will be obvious that a spectacle, with its temples folded and having a vertical dimension greater than that of the normal vertical dimension of the open end 16 of the case, may be inserted in the case by stretching the elastic material 15 so that the spectacle may be forced in through the open end of the case and be held therein by the yielding engagement of the elastic material 15 with the top portion of the spectacle. The

2

body member is preferably formed so that the vertical dimension of the case gradually increases in size from the open end 16 toward the closed end. Since the bottom edge portion of the spectacle case is relatively non-yielding in a vertical direction, a spectacle may be readily inserted or removed from the case by sliding it along the non-yielding bottom edge and forcing it into or out of yielding engagement with the elastic material 15. It will be apparent, therefore, that the spectacle will be retained in the case by the yielding engagement of the elastic member 15 so that it will not accidentally fall out of the case in handling. Since the elastic material 15 is capable of being stretched a substantial amount in a vertical direction, spectacles of various vertical dimensions may be accommodated in the case.

In the modification shown in Figs. 3 and 4, the case 20 is formed by uniting two elongated pieces of sheet material 21 and 22, such as by stitching 23, along their lower bottom edges. The piece of elastic material 24 is reversely folded on itself and the adjacent longitudinal edges are secured, respectively, to the upper edges of the walls 21 and 22 as by stitching 25. This structure provides a substantially flat, tubular body member having both ends 25 open for the insertion or removal of a spectacle. The walls 21 and 22 may be formed of any flexible sheet material, such as leather or plastic, or they may be formed of a relatively rigid material joined along their bottom edges so as to provide a track which is substantially V-shaped in vertical section. The bottom edges of the walls 21 and 22 are preferably united along a slightly arcuate line as shown in Fig. 3 so that a spectacle may be inserted at either of the open ends of the case by sliding the spectacle along the track formed by the V-shaped bottom portion. When this is done, the elastic material 24 stretches in a substantially vertical direction so that the elastic material yieldably holds the spectacle against the relatively non-yielding bottom track portion.

From the foregoing, it will be apparent that I am able to attain the objects of my invention and provide a spectacle case of the open end type which will be relatively simple in structure and capable of being manufactured at a relatively low cost. The pieces of elastic material 15 and 24 will, in both forms of the invention, serve to yieldingly and releasably hold the spectacle in the case. The elastic sheet material 15 and 24 may be made of two or more pieces instead of a single piece, as shown on the drawings. This construction, therefore, eliminates the necessity of providing closure flaps or other means for insuring that a spectacle will not accidentally fall out of the case. The various component parts of the case may be readily united by stitching, heat-sealing, cementing, or any other well-known method for uniting parts. Various modifications may obviously be made without departing from the spirit of my invention as pointed out in the appended claims.

55 I claim:

1. A spectacle case comprising a pair of front and rear walls joined along their top and bottom edges to provide a substantially flat, tubular body having an open end for the insertion of a spectacle, said walls being partially cut-away adjacent said open end, and elastic sheet material secured to said walls at the cut-away portions to form a part of the open end of the case whereby a spectacle having a vertical dimension greater than that of the open end may be inserted in the case by stretching the elastic material so that the spectacle will thereby be retained in the case by yielding engagement of the elastic material.

2. A spectacle case comprising a substantially flat, tubular body having an open end into which a spectacle may be inserted, said body having a longitudinally extending bottom edge portion which is substantially V-shaped in vertical section and provides a track which is relatively

non-yielding in a vertical direction, and a reversely folded piece of elastic sheet material having its adjacent longitudinal edges attached to the respective sides of said V-shaped bottom edge portion, whereby a folded spectacle having a vertical dimension greater than that of the open end of the case may be inserted into the open end by stretching the elastic material and sliding the spectacle along the V-shaped bottom edge portion so that the elastic material will yieldingly engage the spectacle and urge it against said bottom edge portion and thereby hold the spectacle in the case.

3. A spectacle case comprising a substantially flat, tubular shaped body having an open end into which a spectacle may be inserted, said body having a longitudinally extending bottom edge portion which is V-shaped in vertical section and is formed of flexible sheet material, and a piece of elastic sheet material which is reversely folded and has its adjacent longitudinal edges connected, respectively, to the two sides of the V-shaped bottom edge portion to form a portion of the case adjacent the open end thereof so that a spectacle having a greater vertical dimension than the open end of the case may be inserted in the open end thereof by stretching the elastic material so that it yieldingly engages the spectacle and holds the latter against said bottom edge portion to retain it in the case.

4. A spectacle case comprising a substantially flat, tubular body formed of sheet material and having front and rear side walls which are connected along the portions at the top, bottom and one end thereof to provide a case having an open end into which a spectacle may be inserted, the upper portions of the front and rear walls adjacent said

5

25

open end being formed of elastic sheet material whereby a spectacle having a vertical dimension greater than that of said open end may be inserted in the case by stretching the elastic material and sliding the spectacle inwardly along the relatively non-yielding bottom of the case, the elastic material resiliently engaging a part of the spectacle for retaining the latter in the case.

5. A spectacle case comprising a substantially flat, tubular body formed of sheet material and having front and rear side walls which are joined along the top, bottom and one end to provide a case having an open end into which a spectacle may be inserted, the vertical dimension of the case increasing from the open end toward the closed end, the upper portions of the front and rear walls being cut-away adjacent the open end of the case, and a piece of elastic sheet material reversely folded and attached to said walls to substantially fill in the cut-away portion whereby a spectacle with its temples folded and having a greater vertical dimension than the normal vertical dimension of said open end may be inserted in the case by stretching the elastic material at the open end and sliding the spectacle inwardly so that the elastic material will yieldingly engage a part of the spectacle to hold it in the case.
